ELECTRIC SWITCH

Alvin W. Krieger, Milwaukee, Wis., assignor to
 Cutler-Hammer, Inc., Milwaukee, Wis., a corporation of Delaware

Application September 27, 1938, Serial No. 231,940

15 Claims. (Cl. 200—11)

This invention relates to improvements in electric switches. Although not limited thereto, the invention relates more particularly to improvements in the structural details and operative characteristics of switches of the so-called fan duty type.

An object of the invention is to minimize the cost and facilitate assembly of the parts of switches of the aforementioned character.

Another object is to minimize the number of different parts required for construction of switches having various different circuit controlling characteristics.

Another object is to provide a rotary switch adapted for alternative use for control of alternating current or direct current circuits.

Another and more specific object is to provide a switch having simple and efficient means for snuffing or smothering any arcs formed incident to interruption of a circuit controlled by the switch, thus increasing the current controlling capacity of the latter.

Another object is to provide stationary and movable switch contact elements of novel form.

Another object is to provide a novel form of metal supporting frame or housing for the switch.

Another object is to provide a single novel means for insuring both a double make and/or break of the controlled circuit in each instance and positive positioning of the movable contact elements of the switch.

Other objects and advantages of the invention will hereinafter appear.

The accompanying drawings illustrate certain embodiments of the invention which will now be described, it being understood that the embodiments illustrated are susceptible of modification in respect of certain details of construction thereof without departing from the scope of the appended claims.

In the drawings, Figure 1 is a side elevation of a three-speed, four-position fan switch constructed in accordance with my invention, the switch parts being shown in "off" position.

Fig. 2 is a top plan view of the switch, with the operating knob or handle and the mounting nuts removed for purposes of illustration.

Fig. 3 is a bottom plan view of the switch shown in Figs. 1 and 2.

Fig. 4 is an exploded perspective view of certain of the stationary and movable parts of the switch, said parts being in relative positions corresponding to second speed of the fan motor or the like (not shown).

Fig. 5 is a top plan view of the insulating

base of the switch, with the combined stationary contact and terminal members attached thereto, the contour of the insulating plate to be superimposed thereon, and the openings in said plate as well as the cross sectional contour of the operating shaft, being illustrated in dotted lines.

Fig. 6 is a vertical sectional view of the switch, with the parts thereof in "off" position as shown in Fig. 1, said view being taken on the line 6—6 of Fig. 3.

Fig. 7 is a vertical sectional view, on the line 7—7 of Fig. 6.

Fig. 8 is a horizontal section, on the line 8—8 of Fig. 7.

Fig. 9 is a top plan view of a switch base like that shown in Fig. 5, but with one of the combined stationary contact and terminal members omitted, to provide a two-speed, three-position fan switch.

Fig. 10 is a fragmentary view, partly in section on a line corresponding to 8—8 in Fig. 7, showing a modified form of stop plate (as compared with Fig. 8, for instance), and illustrating the manner in which the same cooperates with the stop lugs formed upon the supporting frame or housing.

Fig. 11 is a vertical sectional view of a switch which is functionally similar to that shown in Figs. 1 to 8, but differs from the latter in respect of certain structural details.

Fig. 12 is a sectional view on the line 12—12 of Fig. 11.

Fig. 13 is a bottom plan view of the switch shown in Figs. 11 and 12.

Fig. 14 is a top plan view of the insulating base of the switch shown in Figs. 11 to 13, the stationary combined contact and terminal members being shown attached thereto.

Fig. 15 is a side elevational view of a switch quite similar to that shown in Figs. 11 to 14, but modified to provide means for insuring movement of the movable switch parts to one or another of their desired positions upon manual release of the operating knob, one of the frame legs being broken away to show the octagonal form of the operating shaft, and

Fig. 16 is a horizontal section on the line 16—16 of Fig. 15, looking in the direction of the arrows.

Referring first to Figs. 1 to 8, inclusive, the numeral 20 designates the substantially circular top portion of a punched and stamped sheet metal supporting frame or housing, said top portion preferably having formed integrally therewith three leg portions 21, 22 and 23 which are

bent downwardly at substantially right angles thereto. Said legs are respectively provided at the lower ends thereof with reduced portions 21^a, 21^b, 22^a, 22^b and 23^a, 23^b, the reduced portions 21^a, 22^a and 23^a providing pairs of horizontal shoulders which engage the upper surface of a flat punched insulating base 24 to insure against upward displacement of the latter with respect to the top portion 20 of the metal frame; said reduced portions 21^a, 22^a and 23^a also providing pairs of vertical shoulders which fit rather closely between the side walls of the equally spaced peripheral notches 24^a, 24^b and 24^c of like dimensions formed in base 24 to restrain the latter against rotary displacement relatively to the frame.

The aforementioned reduced portions 21^b, 22^b and 23^b serve as lugs which are bendable inwardly over the lower surface of base 24 to positively retain the latter in assembled relation to the frame.

As best illustrated in Fig. 5, there are attached to base 24 three combined contact and terminal members of identical form, the contact portions 25 of said members being seated flatwise upon the upper surface of the base and being attached thereto as by means of pairs of lugs 25^a which penetrate pairs of openings in the base and are bent inwardly toward each other in the manner illustrated in Fig. 3. Formed integrally with contact portions 25, and bent downwardly at substantially right angles thereto, are the wiring terminal lugs 25^b, which are respectively accommodated by a corresponding number of substantially rectangular openings formed in the base. Lugs 25^b are provided with the usual openings or perforations (see Fig. 1) to facilitate attachment of the bared ends of circuit wires thereto as by soldering or brazing.

As will be apparent from Fig. 5 the adjacent ends of the three contact portions are arranged substantially in the form of an arc. Diametrically opposed to the three contact portions 25 is a flat contact portion 26 of arcuate contour, said contact portion 26 having three lugs 26^a, 26^b, and 26^c which penetrate correspondingly located openings in base 24 and are bent inwardly over the lower surface of the latter, as shown in Fig. 3. Formed integrally with contact portion 26, and bent downwardly at substantially a right angle thereto, is a wiring terminal lug 26^d, which is accommodated by a substantially rectangular opening formed in base 24.

Base 24 may, if desired, be provided with a centrally located circular opening 24^d to accommodate a reduced lower end portion of shaft 17 to assist in centering the latter. As best illustrated in Figs. 6 and 7, however, the shaft 17 is provided with a flat lower end which is positioned in a plane slightly above the upper surface of base 24, said shaft being supported and centered by means independent of base 24, as hereinafter described. Pressed or extruded upwardly from base 24 at diametrically opposite points 24^e, 24^f (Figs. 3 and 6), are a pair of substantially cylindrical bosses 24^g, 24^h (Figs. 5 and 6), the flat upper surfaces of which are preferably located in a plane slightly above the plane of the aforementioned contacts 25 and 26.

Superimposed upon base 24 and adapted to seat upon the contacts 25 and 26 is a relatively thin, flat, punched plate 27 of insulation—said plate having a circularly arranged series of eight equally spaced openings—one diametrically opposed pair of said openings being designated 27^x, 27^x;

and the three other diametrically opposed pairs of openings being respectively designated 27^a, 27^a; 27^b, 27^b and 27^c, 27^c. Plate 27 is provided with three equally spaced peripheral notches 27^d, 27^e and 27^f, which are respectively adapted to register with the relatively smaller notches 24^b, 24^c and 24^a, in base 24, as best illustrated in dotted lines in Fig. 5. Said peripheral notches in plate 27 are respectively adapted to accommodate the aforementioned leg portions 22, 23 and 21 of the metal frame (as best illustrated at 21, 27^f in Fig. 1) to prevent rotary displacement of plate 27 relatively to the metal frame and base 24.

Plate 27 may be provided with an indicating notch as shown in dotted lines at 27^g in Fig. 4 to facilitate proper positioning thereof with respect to base 24. However, for purposes of assembly it is sufficient to note that notch 27^d is the only one having a pair of openings (27^x, 27^x) definitely aligned and centered with respect thereto, it being understood that plate 27 must be so positioned as to bring notch 27^d into alignment with notch 24^b in base 24 (Fig. 5). This will insure positioning of the openings 27^x, 27^x in alignment with the cylindrical extrusions or bosses 24^g, 24^h; and one series of openings 27^a, 27^b and 27^c will be aligned with the arcuate contact 26, as illustrated in dotted lines in Fig. 5, the other series of openings 27^a, 27^b and 27^c being aligned with the three contacts 25.

To insure against substantial upward displacement of plate 27, I preferably shear and bend inwardly from the respective frame legs 21, 22 and 23 tongues 21^c, 22^c and 23^c, the lower ends of which tongues closely overlie the upper surface of plate 27, in the manner best illustrated at 22^c in Fig. 6.

Superimposed upon plate 27, for rotation with respect thereto, is a relatively thick punched insulating plate 28, of a size sufficiently large to overlie the aforementioned circular series of openings in plate 27, as best illustrated in Fig. 8, but small enough to provide ample clearance between the same and frame legs. Plate 28 is provided with a centrally located square opening 28^a to accommodate with a sliding fit the lower portion of shaft 17 of corresponding form in cross section, to provide for rotation of said plate by said shaft. Plate 28 is provided with a pair of diametrically opposed circular openings 28^b and 28^c, said openings being arranged in a line at right angles to two of the sides of opening 28^a (see Fig. 4). Loosely positioned within openings 28^b 28^c are a pair of spherical metal contactors or balls 29, of a diameter substantially greater than the thickness of plate 28. The arrangement is such that the openings 28^b, 28^c and the balls 29 located therewithin will be aligned with one or another of the pairs of diametrically opposed openings in plate 27 in the several operative positions of the switch parts, as hereinafter described. In practice I prefer to provide plate 28 with cut away portions, as indicated by the straight sides 28^d and 28^e, primarily to reduce the amount of insulation required, with consequent reduction in the weight or inertia of this part.

Superimposed upon plate 28, and adapted to seat against the portions of balls 29 which project above said plate, is a punched sheet metal conductor or plate 30 of annular form. Plate 30 is provided with a relatively large centrally located circular opening 30^a, which affords ample electrical clearance between said plate and shaft 17. In a line at right angles to the line of engagement of plate 30 with balls 29 are a pair of

5 diametrically opposed, upwardly projecting, hemispherical bosses 30^b and 30^c formed integrally with said plate. Superimposed upon plate 30 is a flat punched insulating plate 31 of substantially the same contour as plate 28, but preferably relatively thinner than the latter. Plate 31 is provided with a centrally located square opening 31^a (like the opening 28^a in plate 28) to accommodate shaft 17 and to provide for driving of 10 the former by the latter. Plate 31 is also provided with a diametrically opposed pair of circular openings 31^d and 31^e which are adapted to accommodate the respective bosses 30^b and 30^c formed on conductor plate 30, to constrain the 15 latter to rotate in either direction with the former. I also prefer to provide plate 31 with cut away portions, as indicated by the straight sides 31^d, 31^e.

20 As illustrated in Fig. 4, the plates 28, 30 and 31 are so assembled that the flat sides 31^d, 31^e of plate 31 are angularly displaced substantially 90 degrees with respect to the flat sides 28^d, 28^e of plate 28. Inasmuch as plates 28, 30 and 31 are restrained against rotary displacement relatively 25 to each other, it will be apparent that the flat lower surface of plate 30 is adapted to engage the projecting upper ends of balls 29 at points on the former spaced substantially 90 degrees from the respective bosses 30^b and 30^c.

30 Shaft 17 is provided at an intermediate point in its length with a reduced portion 17^a of circular form in transverse cross-section, the groove required to form said reduced portion providing a pair of spaced horizontal shoulders, as best illustrated in Figs. 6, 7 and 8. Insertable into said groove with a rather close fit is a horseshoe-shaped metal washer 32 which has its adjacent end portions bent toward each other, as shown in Fig. 8, to substantially entirely surround the reduced portion 17^a of the shaft and to resist accidental displacement of said washer.

35 Strung upon the lower end of shaft 17, in a relation to other of the switch parts as illustrated in Fig. 4, is a flat sheet metal stop plate 33 having a square opening 33^a to accommodate the shaft 17 whereby the former is driven by the latter. Also strung upon shaft 17 and interposed between the lower surface of stop plate 33 and the upper surface of insulating plate 31 is a coiled compression spring 34, the upper and lower end coils of which spring are preferably arranged in parallel horizontal planes by the winding operation, as shown in Fig. 4. Stop plate 33 is formed as shown in Figs. 4 and 8 to provide a pair of spaced radial shoulders 33^b and 33^c, the shoulder 33^b being engageable with an integral lug 20^a struck downwardly from the top portion 20 of the metal frame, to limit the degree of clockwise movement of shaft 17 and its associated parts; and the shoulder 33^c being engageable with a second integral lug 20^b struck downwardly from top portion 20, to limit the degree of counterclockwise movement of the shaft.

40 The range of rotary movement thus provided for shaft 17 is such as to provide four definite operative positions for the switch parts. That is to say, from an "off" position wherein the ball contactors 29 are engaged with the respective bosses 24^b and 24^c, the parts may be rotated clockwise (Fig. 5) to three other operative positions, wherein one of the ball contactors 29 sequentially assumes positions alined with the

5 openings in plate 27, as represented by the dotted lines 27^a, 27^b and 27^c upon the contact 26 in Fig. 5, while the other ball contactor 29 is simultaneously moved to sequentially assume positions aligned with other openings in plate 27, as represented by the dotted lines 27^a, 27^b and 27^c upon the three contacts 25 in Fig. 5. Assuming proper connection of the switch terminals in the circuit of a fan motor, the arrangement is such that the motor circuit may 10 be interrupted, or the motor circuit may be commutated (through the medium of suitable resistances, not shown) to provide for high, medium or low speed operation of the motor.

15 As best illustrated in Figs. 6 and 7 the top portion 20 of the frame is provided with a centrally located circular opening 20^c which is adapted to accommodate the reduced lower end 35^a of an externally threaded hollow metal bushing 35, said reduced end 35^a being upset over the lower surface of top portion 20 to rigidly and non-rotatably attach said parts to each other. The circular wall of opening 35^a is preferably notched in a well known manner to provide a better interlock with the upset end 35^a 25 of the bushing.

20 The lower end portion of bushing 35 is preferably provided with an annular recess 35^b to accommodate and provide a bearing for the aforementioned washer 32, to limit the degree 30 of upward displacement of shaft 17. Shaft 17 extends upwardly beyond bushing 35, and said shaft is provided with a second groove or reduced portion 17^b which is adapted to accommodate a relatively thin sheet metal washer 36 35 of horseshoe shape. The free ends of washer 36 are bent toward each other, or clinched, to prevent accidental displacement thereof from shaft 17. Washer 36 bears upon the upper end of bushing 35 to restrain shaft 17 against substantial downward displacement. As best illustrated in Fig. 7, the relatively thick washer 36 40 rotatably bears within the annular recess 35^b to maintain shaft 17 in properly centered relation to bushing 35; the diameter of the opening or 45 passage 35^c in bushing 35 being such as to provide a rotatable bearing for shaft 17 at the four vertical corners or edges of the latter, to further insure centering of said shaft.

50 Shaft 17 is provided at its upper end with a tapped recess 17^a (Fig. 6). A molded insulating knob or handle 37 is provided. The knob as shown is of the form illustrated in Design Patent No. 108,723, granted March 8, 1938, to C. B. Stevens. A knob of any other suitable form 55 may of course be employed if desired. Knob 37 is provided with a recess 37^a of square form in transverse cross section to non-rotatably receive the upper end portion of shaft 17. Opening to the upper surface of knob 37 is a countersink or recess 37^b which is adapted to accommodate with a press fit a circular disk 38, preferably of insulating material of any desired color, either like or contrasting with the color 60 of knob 37, to provide a neat and finished appearance of the latter. Opening to recess 37^b is a cylindrical recess 37^c which is adapted to accommodate the head 39 of a fastening screw, the shank 39^a of which penetrates an opening 70 37^d leading from recess 37^c to recess 37^a, said shank taking into the aforementioned tapped recess 17^a in shaft 17 to retain knob 37 in assembled relation to shaft 17. A known form 75 of split lock washer 40 preferably underlies the

head 39 of the fastening screw to prevent accidental loosening of the latter.

Prior to attachment of handle 37 to the switch, the latter is mounted upon a suitable casing or panel provided with a single mounting hole, the upper clamping nut 41 being temporarily removed and the nut 42 being adjusted to the desired position, depending upon the thickness of the panel or casing. Preferably the mounting is such that the upper surface of nut 41 when in clamping position against the panel is substantially flush with the upper end of bushing 35. In practice I prefer to provide the switch frame with integral struts or indentations 21^d, 22^d and 23^d at the points of juncture of the leg portions 21, 22 and 23 with the top portion 20 to strengthen the frame as a whole and to prevent accidental bending or deformation of said leg portions after assembly of the switch parts.

With particular reference to Fig. 8, it will be understood that although I have described a four-position switch having a single "off" position and three "on" positions, wherein the direction of rotation of the shaft must be reversed upon attainment of each extreme rotary position thereof, it is possible by a slight modification of one of the parts to provide a switch mechanism having two alternative "off" positions, and to provide for rotation of the movable switch parts in either direction from any given rotary position thereof to another. Such modification merely involves the provision of a plate 33 having the outer or laterally extending portion thereof removed, as indicated by the dotted line 33^d in Fig. 8, whereby the stop shoulders 33^b and 33^c are eliminated.

Also as shown in Figs. 9 and 10 a two-speed, three-position fan switch may be provided by substituting for the metal stop plate 33 aforescribed a metal stop plate 43 wherein the radial stop shoulders 43^b and 43^c for engagement with the respective stop lugs 20^a and 20^b are less widely spaced, angularly, than are the aforescribed stop shoulders 33^b and 33^c of stop plate 33. For this purpose, one of the combined stationary contact and terminal members 25 (the left-hand contact and terminal member of Fig. 5) is preferably omitted, as shown in Fig. 9, the insulating base plate 24 being identical with that aforescribed. Such modified switch mechanism may be in all other respects exactly like that aforescribed.

From the foregoing description it will be apparent that the conductor plate 30 which is at all times biased into engagement with the ball contactors 29 acts as a connecting bus member for the latter. Due to the fact that insulating plate 27 is maintained stationary it is to be noted that upon rotation of plate 28 by shaft 17 the ball contactors 29 are obliged to ride upwardly over the walls of each diametrically opposed pair of openings 27^x, 27^y; 27^a, 27^b, etc., and are carried by plate 28 into alignment with the next succeeding diametrically opposed pair of such openings. As the ball contactors 29 fall into each pair of openings a definite "feel" or position indication of the switch mechanism is provided.

As will be apparent from consideration of Figs. 6 and 7, upon movement of ball contactors 29 from each "on" position thereof, a double break of the controlled circuit is provided. At the same time the movable plate 28 cooperates with the stationary plate 27 to close the gaps resulting from movement of ball contactors 29 outwardly

from the diametrically opposed pairs of openings in plate 27, so that any arcs formed incident to disengagement of the ball contactors from the stationary contacts are effectively smothered or snuffed. This arrangement provides a relatively high current controlling capacity for the switch, and minimizes pitting and erosion of the contacts and contactors, thereby increasing the life of the switch.

In practice the bushing 35 is provided with a pair of parallel sides 35^d, 35^e (Figs. 1 and 2), the opening in the casing or panel having corresponding flat sides for cooperation therewith to prevent relative rotation of the bushing within said opening. Also in practice a suitable indicating plate (not shown) is non-rotatably mounted upon bushing 35 and clamped in position by nut 41, said indicating plate having suitable legends for cooperation with knob 37 to indicate the electrical condition of the circuit or circuits controlled by the switch.

In Figs. 11 to 14, inclusive, I have shown a modified form of three-speed, four-position fan switch. Thus I provide a flat, punched insulating base or plate 44 of substantially circular contour, plate 44 having three equally spaced peripheral notches 44^a, 44^b and 44^c formed therein to accommodate the reduced lower ends 45^a, 46^a and 47^a of the respective frame arms, two of which are shown at 46 and 47 (Figs. 11 and 12). Said frame arms are provided at opposite sides of the reduced end portions thereof with horizontal shoulders which are adapted to seat upon the upper surface of base 44, and said end portions 45^a, 46^a and 47^a are bent inwardly over the lower surface of base 44 to secure the frame and the base in assembled relation. Said arms are formed integrally with and bent downwardly at right angles to the plane of the flat top portion 48 of the frame.

As shown in Figs. 13 and 14, there is superimposed upon the upper surface of base 44 the arcuate portion 49 (Fig. 14) of a punched sheet metal member, the integral wiring terminal portion 49^a of which is bent downwardly at substantially a right angle to said arcuate portion and penetrates an opening provided in base 44 for exposure below the lower surface of the latter (Figs. 12 and 13). Arcuate portion 49 and base 44 are provided with three sets of aligned openings 50 arranged in equally spaced arcuate relationship to each other, said sets of openings being respectively adapted to accommodate the shanks of three rivets the heads 50 of which clamping engage said arcuate portion 49 and the hollow shanks 50^a of which are upset over the lower surface of base 44 to rigidly secure said parts in assembled relation.

Arranged in diametrically opposed relationship to arcuate portion 49 is an arcuately arranged series of three punched sheet metal members 51 of like form, said members having integral terminal portions 51^a bent downwardly with respect thereto and penetrating suitable openings provided in base 44 for exposure below the lower surface of the latter. Another series of three rivets have their heads 50 superimposed upon said portions 51, the hollow shanks 50^a of said rivets penetrating aligned openings provided in the respective portions 51 and in base 44, and said shanks being upset over the lower surface of base 44 (Figs. 12 and 13) to rigidly secure said parts in assembled relation. The terminal portions 49^a and 51^a are provided with the usual openings 49^b and 51^b to facilitate looping attach-

ment and soldering of the circuit wires (not shown).

Pressed or extruded from base 44 and projecting a substantial distance above the upper surface thereof is a pair of diametrically opposed substantially cylindrical bosses 44^d and 44^e which are respectively positioned between the adjacent ends of the two arcuate series of rivet heads 50 (Fig. 14). Superimposed upon base 44 and of corresponding circular contour is a flat punched insulating plate 52, which is preferably of less thickness than said base (Figs. 11 and 12). Plate 52 is provided with a circularly arranged series of eight equally spaced circular openings, certain of which are shown at 52^a in Figs. 11 and 12; said plate being adapted to seat upon the portions 49 and 51 of the aforementioned sheet metal members, and said openings being adapted to accommodate and rather closely surround the six rivet heads 50 and the bosses 44^d and 44^e (Fig. 14). The arrangement is such that the flat upper surfaces of the rivet heads 50 (Fig. 12) and the flat upper surfaces of bosses 44^d and 44^e (Fig. 11) are offset downwardly to a substantial degree 25 with respect to the upper surface of plate 52.

Plate 52 is provided with three equally spaced peripheral notches to accommodate the relatively wide portions of the frame arms, one of said notches being shown at 52^b (Fig. 11) in assembled relation with arm 46. The straight side walls of the respective notches cooperate with the side edges of the frame arms to restrain plate 52 against rotation relatively to base 44 and the switchframe. Plate 52 is also provided with a centrally located circular opening 52^c (Figs. 11 and 12) which provides rotatable clearance for the lower end of the operating shaft 53, which, as indicated in Figs. 11 and 12, is of substantially square form in transverse cross section.

The flat upper portion 48 of the switch frame is provided with a centrally located opening 48^c (Figs. 11 and 12) which is adapted to receive the reduced lower end of an externally threaded hollow metal bushing 35—which may be identical with the corresponding bushing aforescribed—said reduced lower end being upset over the lower surface of frame portion 48, as shown at 35^a in Figs. 11 and 12, to rigidly and non-rotatably secure said parts to each other. Shaft 53 is provided at an intermediate point in its length with a peripheral groove 53^a, within which a horse-shoe-shaped washer 54 is loosely inserted. The lower end of bushing 35 is provided with an annular recess 35^b the peripheral wall of which accommodates washer 54, whereby lateral displacement of said washer from shaft 53 is prevented. The flat upper end wall of recess 35^b also cooperates with washer 54 to prevent substantial upward displacement of shaft 53. In practice the flat lower end of shaft 53 is adapted to bear against or closely approach the upper surface of base 44. Also it is to be understood that the opening or passage 35^c in bushing 35 is of such circular size in transverse cross section as to provide a rotatable bearing for the shaft 53 at the four transverse corners of the latter, whereby proper positioning or centering of the shaft is insured.

Strung upon the lower end of shaft 53 and adapted to bear against the upset end 35^a of bushing 35 is a flat punched metal plate 33, which may be identical with the correspondingly designated part aforescribed. Plate 33 is associated with shaft 53 for positive rotation by the latter, and said plate is provided with a pair of angularly spaced radial shoulders adapted for coop-

eration with a pair of spaced integral lugs struck downwardly from frame portion 48 (one of said lugs being shown at 48^a in Fig. 11) to limit the degree of rotary movement of shaft 53 in each direction, as described in connection with the device of Figs. 1 to 8, inclusive.

Strung upon the lower end of shaft 53 and adapted to be centered by the latter is an annular metal washer or plate 55 which abuts plate 33, and also strung thereon is an annular insulating washer 56 of a shape and size similar to washer 55 and underlying the latter. It is to be understood that a second insulating annulus like 56 may be substituted for the metal washer 55, or a single insulating annulus corresponding in thickness or depth to the combined thicknesses of washers 55 and 56 may be employed.

Also strung upon the lower end of shaft 53 and underlying insulating washer 56 is a flat punched insulating plate 57 which is preferably of substantially circular contour and of a size to at least partially overlie the aforementioned arcuately arranged groups of rivet heads 50 which form the stationary contacts of the switch. The substantially square opening in plate 57 cooperates with shaft 53 to provide for positive rotation of the former with the latter. Underlying plate 57 is a bridging contact member 58, which is preferably of substantially annular form and is composed of a suitable resilient conducting metal or alloy, such as phosphor bronze.

Member 58 is so formed that diametrically opposed portions 58^a and 58^b thereof are adapted to abut the lower surface of plate 57, said plate having a pair of openings 57^a and 57^b formed therein (Fig. 12), and member 58 having lugs 58^c and 58^d formed integrally therewith and extending upwardly through said openings 57^a and 57^b, lugs 58^c and 58^d being bent outwardly over plate 57 to positively unite member 58 to plate 57 for rotation with the latter. Member 58 is bent or deformed to provide a pair of diametrically opposed low points angularly displaced substantially 90 degrees from the respective portions 58^a and 58^b thereof, said low points being further deformed, as shown at 58^e and 58^f in Figs. 11 and 12, to provide downwardly convexed movable contact portions. Upon complete assembly of the switch parts as shown in Figs. 11 and 12 the bridging contact member 58 is compressed or distorted to a predetermined degree.

Shaft 53 is provided at its upper end with a tapped recess 53^b (Fig. 11) to accommodate a securing screw (such as the screw 39, Figs. 6 and 7) employed for attaching a knob or handle, such as the knob 37 aforescribed. The plate 52 is adapted for assembly in only one rotary relationship to base 44 (as pointed out in the description of plate 27 and base 24 of Figs. 4 and 5). The bushing 35 of Figs. 11 and 12 may be provided with clamping nuts 41, 42, as shown in Fig. 6, to provide for one-hole mounting of the switch to a panel or other suitable support. As shown in Fig. 11 the top portion of 48 of the metal frame has an integral lug 48^d bent downwardly at substantially a right angle thereto and in diametrically opposed relationship to the frame arm 46, said lug 48^d having utility only in conjunction with the modified form of switch mechanism shown in Figs. 15 and 16.

With reference to Fig. 11, wherein the portions 58^a and 58^b are engaged with the insulating bosses or projections 44^d and 44^e to provide for "off" or circuit interrupting positioning of the switch parts, it will be understood that upon

clockwise rotation of the shaft 53 the convex lower surfaces of the movable contact portions 58^e and 58^f will first ride upwardly, with a cam-like action, over one side wall of each of the 5 respective openings 52^a in plate 52, thus further stressing the downwardly bent portions of the annular bridging contact member 58, and upon continued clockwise rotation of shaft 53 said convex contact portions 58^e and 58^f will move 10 with a similar, but reverse, cam-like action into bridging engagement with the first succeeding diametrically opposed pair of rivet head stationary contacts 50. Due to the temporary increase 15 of the degree of compression of member 58 and the subsequent release of such additional pressure (upon attainment of another operative position of the switch parts) a definite "feel" is provided, to indicate to the switch operator that such operative position has been attained.

20 Moreover, as best illustrated in Fig. 12, upon movement of the portions 58^e, 58^f of the bridging contactor 58 out of circuit completing engagement with one pair of diametrically opposed rivet head contacts 50, said portions are obliged to 25 move upwardly over the walls of a pair of openings 52^a in plate 52 and then laterally away from said openings, thus providing a relatively large gap across insulating surfaces which assists in cooling and snuffing any arcs formed incident to 30 interruption of the circuit or circuits controlled by the switch.

The modified form of switch illustrated in Figs. 15 and 16 is in many respects like that shown in Figs. 11 to 14, inclusive, and like parts 35 in the two devices have been given corresponding numerals of reference. In Figs. 15 and 16, however, the top portion 48 of the switch frame has been modified to provide a second pair of downwardly bent integral lugs 48^e and 48^f which are 40 alined with the respective lugs 48^a and 48^b, it being noted that lugs 48^e and 48^f are spaced farther from the center of portion 48 than are the lugs 48^a and 48^b, whereby the former provide rotatable clearance for the stop plate 59. Stop plate 59 is substantially like the stop plate 33 aforescribed, and is provided with radial shoulders 59^b and 59^c 45 for engagement with the respective lugs 48^a and 48^b to limit the degree of rotation of the switch shaft 60, which in this case is of octagonal form 50 in transverse cross section. Accordingly the stop plate 59 is provided with an octagonal opening 59^a (Fig. 16) to accommodate said shaft whereby a positive driving connection between said parts is provided.

55 As shown in Fig. 16 a pair of leaf springs 61 is provided, one of said springs engaging one side of shaft 60 and having portions adjacent to the respective ends thereof engaged under tension with the alined lugs 48^b and 48^f. The other spring 61 is engaged with the other side of shaft 60 and has portions adjacent to the respective ends thereof engaged under tension with the alined lugs 48^a and 48^e. The springs 61 thus act to 60 resiliently bias shaft 60, and the switch parts controlled thereby, to the nearest one of its various predetermined positions (within the range provided by the shape of stop plate 59) upon release of the knob or handle. Springs 61 likewise 65 cooperate with shaft 60 to provide a predetermined degree of resistance to rotation thereof within its range, such resistance to rotation being cumulative with respect to the resistance to turning of said shaft afforded by the aforementioned 70 silent cam action of contact portions 58^e and 58^f.

with respect to the walls of openings 52^a in plate 52.

As shown in Figs. 15 and 16, the frame arm 46 serves as an abutment to prevent endwise displacement of springs 61 in one direction, and downwardly extending lug 48^d serves as an abutment to prevent endwise displacement of said springs in the opposite direction. Loosely strung upon shaft 60 is a relatively thin punched plate 63 (Fig. 15) of insulating material, said plate 10 providing a suitable barrier between the springs 61 and the lugs 58^c and 58^d by which bridging contact member 58 is attached to plate 57; and plate 63 likewise prevents downward displacement of springs 61. Interposed between insulating plates 63 and 57 is an annular insulating disk or washer 64 of smaller diameter and less thickness than plate 57, said washer serving to insure proper clearance between plate 63 and the aforementioned lugs (one of which is shown at 20 58^d in Fig. 15).

The knob 62 as shown in Fig. 15 comprises a lower cylindrical portion 62^a of relatively large diameter and an upper substantially cylindrical portion 62^b of relatively smaller diameter. An 25 integral portion 62^c tapers laterally toward the periphery of portion 62^a and another integral portion 62^d flares laterally and extends beyond the portion 62^a to provide a handle or lever to facilitate operation of the switch. A passage (not 30 shown) extends upwardly through portions 62^a and 62^b of knob 62, the lower portion of said passage being of octagonal form in transverse cross section to non-rotatably accommodate the upper end of shaft 60, the upper portion of said passage being adapted to accommodate the head and shank of a securing screw which takes into a tapped opening (not shown) in the upper end of said shaft. Knob 62 may be provided with a 35 countersink or recess opening to its upper surface to accommodate an insulating disk or the like to conceal the screw head and thus provide a more finished appearance to the knob, in the manner illustrated in Figs. 6 and 7. It will be understood that a knob like that shown in Figs. 40 45 6 and 7 may be employed in lieu of that shown in Figs. 15 and 16, provided that the knob is furnished with an octagonal recess of proper size opening to the lower surface thereof.

What I claim as new and desire to secure by 50 Letters Patent is:

1. In an electric switch, in combination, an insulating base, a plurality of combined contact and terminal members having contact portions superimposed upon said base and having wiring terminal portions penetrating said base and exposed below the lower surface of the latter, certain of said contact portions being common to one of said wiring terminal portions, a flat punched insulating plate superimposed upon said base and restrained against transverse movement relatively thereto, said plate having a plurality of groups of openings forming opposed pairs, certain openings of one group overlying the contact portions common to said one wiring terminal portion to thereby provide for exposure of restricted areas of said contact portions, other of said contact portions being individual to their respective wiring terminal portions, certain openings of another group overlying the individual contact portions last mentioned to provide for exposure of restricted areas of the latter, an opposed pair of openings located adjacent to one end of each of the respective groups being adapted to overlie only the material of said in- 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920

5 insulating base, a bridging contactor having a pair of convex end portions movable jointly into and out of alinement with the respective pairs of opposed openings in said plate to provide for circuit interruption or for completion of a plurality of different circuit connections in sequence, and an insulating member associated with said bridging contactor for guiding and controlling such movements of the latter.

10 2. In an electric switch, in combination, an insulating base, a plurality of combined contact and terminal members having portions thereof exposed at the upper surface of said base, said members having sheet metal terminal portions penetrating said base and exposed below the lower surface of the latter, a flat punched insulating plate superimposed upon said base and restrained against rotation relatively thereto, said plate having a circularly arranged series of equally spaced 15 openings formed therein to provide access to limited areas of the exposed portions of said members at the upper surface of said base, said base having a diametrically opposed pair of bosses formed integrally with the upper surface thereof, 20 one pair of said plate openings being alined with said bosses, a second insulating plate positioned above said plate first mentioned and rotatable relatively to the latter, and a diametrically opposed pair of convex contactor elements movable 25 with said second plate and resiliently biased downwardly with respect thereto, said contactor elements being electrically connected with each other and the same being movable jointly into and out of alinement with respective diametrical- 30 ly opposed pairs of openings in said plate first mentioned, to thereby provide for circuit interruption or for completion of a plurality of different circuit connections in sequence.

3. In a rotary electric switch, in combination, 40 a punched and stamped sheet metal frame having a flat top portion and a plurality of equally spaced arms bent downwardly at substantially right angles thereto, said arms having lower ends of reduced width, a punched insulating base having peripheral notches to accommodate said reduced ends of the arms, said reduced ends being bent inwardly over the lower surface of said base to retain said parts in assembled relation, a plurality of combined contact and terminal members having portions thereof exposed at the upper surface of said base, said members having sheet metal terminal portions penetrating said base and exposed below the lower surface of the latter, a flat punched insulating plate superimposed upon said base and restrained from rotation 45 relatively to the latter, said plate having a circularly arranged series of equally spaced openings formed therein to provide access to exposed portions of said members at the upper surface 50 of said base, said base having a diametrically opposed pair of bosses formed integrally with the upper surface thereof, the upper ends of said bosses being located substantially in the plane of said contact portions, one pair of said plate 55 openings being alined with said bosses, a second insulating plate positioned above said plate first mentioned and rotatable relatively to the latter, a pair of diametrically opposed convex contactor elements movable with said second plate and re- 60 siliently biased downwardly with respect thereto, said contactor elements being electrically connected with each other and the same being movable jointly into and out of alinement with the respective diametrically opposed pairs of openings 65 70 in said plate first mentioned, to thereby provide 75

for circuit interruption or for completion of a plurality of different circuit connections in sequence, an externally threaded hollow metal bushing carried by said top portion of the frame, and a shaft of polygonal form in transverse cross section adapted to bear within said bushing, said shaft having a positive driving connection with said second insulating plate. 5

4. In a rotary electric switch, in combination, 10 a punched and stamped sheet metal frame having a flat top portion and a plurality of equally spaced arms bent downwardly at substantially right angles thereto, said arms having lower ends of reduced width, a punched insulating base having peripheral notches to accommodate said reduced ends of the arms, said reduced ends being bent inwardly over the lower surface of said base to retain said parts in assembled relation, a plurality of combined contact and terminal members having portions thereof exposed at the upper surface of said base, said members having sheet metal terminal portions penetrating said base and exposed below the lower surface of the latter, a flat punched insulating plate superimposed upon said base and restrained from rotation 15 relatively to the latter, said plate having a circularly arranged series of equally spaced openings formed therein to provide access to exposed portions of said members at the upper surface of said base, said base having a diametrically opposed pair of bosses formed integrally with the upper surface thereof, one pair of said plate openings being alined with said bosses, a second insulating plate positioned above said plate first mentioned and rotatable relatively to the latter, 20 a pair of diametrically opposed convex contactor elements movable with said second plate and resiliently biased downwardly with respect thereto, 25 said contactor elements being electrically connected with each other and the same being movable jointly into and out of alinement with the respective diametrically opposed pairs of openings 30 in said plate first mentioned, to thereby provide for circuit interruption or for completion of a plurality of different circuit connections in sequence, 35 an externally threaded hollow metal bushing carried by said top portion of the frame, a shaft of polygonal form in transverse cross section adapted to bear within said bushing, said shaft having a positive driving connection with 40 said second insulating plate, a flat punched sheet metal plate with which said shaft has a positive driving connection, said metal plate having angularly spaced radial shoulders formed thereon, and a pair of spaced shoulders extending downwardly from said top portion of the frame and with which said radial shoulders are adapted to engage selectively to limit the degree of rotation 45 of said shaft in each direction. 55

5. In a rotary electric switch, in combination, 60 an insulating base, a flat punched insulating plate superimposed upon said base, said plate having a circularly arranged series of eight equally spaced openings formed therein, a plurality of combined contact and terminal members secured 65 to said base, said members having diametrically opposed pairs of contact portions alined with and accessible through certain of said plate openings, the terminal portions of said members extending downwardly through said base and being accessible below the lower surface of the latter, one diametrically opposed pair of said plate openings being free from contact portions, means for restraining said base and said plate against relative rotation, a second insulating plate superim- 70 75

posed upon said plate first mentioned and rotatable with respect thereto, said second plate having a diametrically opposed pair of openings adapted for selective alinement with the pairs of openings in said first plate, a ball contactor positioned within each opening in said second plate, a metal plate superimposed upon said ball contactors to provide an electrical connection therebetween, spring means providing a continuous downward bias of said metal plate, and a rotatable shaft having a positive driving connection with said second insulating plate.

6. In a rotary electric switch, in combination, an insulating base, a flat punched insulating plate superimposed upon said base, said plate having a circularly arranged series of eight equally spaced openings formed therein, a plurality of combined contact and terminal members secured to said base, said members having diametrically opposed pairs of contact portions alined with and accessible through certain of said plate openings, the terminal portions of said members extending downwardly through said base and being accessible below the lower surface of the latter, one diametrically opposed pair of said plate openings being free from contact portions, means for restraining said base and said plate against relative rotation, a second insulating plate superimposed upon said plate first mentioned and rotatable with respect thereto, said second plate having a diametrically opposed pair of openings adapted for selective alinement with the pairs of openings in said first plate, a ball contactor positioned within each opening in said second plate, a metal plate superimposed upon said ball contactors to provide an electrical connection therebetween, spring means providing a continuous downward bias of said metal plate, a rotatable shaft having a positive driving connection with said second insulating plate, a metal frame providing a bearing for said shaft, said frame having a pair of spaced shoulders formed integrally therewith and positioned therewithin, and a metal stop plate with which said shaft has a positive driving connection, said stop plate having angularly spaced radial shoulders respectively adapted for engagement with said frame shoulders to limit the range of rotary movement of said shaft.

7. In a rotary electric switch, in combination, an insulating base, a flat punched insulating plate of corresponding contour superimposed upon said base, said plate having a plurality of pairs of diametrically opposed openings formed therein and arranged in a circular series in equally spaced relationship to each other, said base having a pair of substantially cylindrical bosses formed thereon and alined with one diametrically opposed pair of openings in said plate, a plurality of one-piece combined contact and terminal members each having a terminal portion penetrating said base and exposed below the lower surface of the latter, one of said members having a flat group contact portion underlying a plurality of openings in said plate at one side of said cylindrical bosses, other of said members having flat individual contact portions underlying a plurality of other openings in said plate at the other side of said bosses and respectively diametrically opposed to said group of contact openings, a second punched insulating plate having a diametrically opposed pair of openings, a ball contactor positioned within each opening last mentioned and of substantially greater diameter than the thickness of said sec-

ond plate, a metal plate superimposed upon said ball contactors and adapted to provide an electrical connection therebetween, a third punched insulating plate superimposed upon said metal plate and having a positive driving and centering connection with the latter, a rotatable shaft of polygonal form in transverse cross section having a positive driving and centering connection with said second and third mentioned insulating plates, means comprising a metal frame for supporting said shaft in centered position independently of said base, and a coiled spring surrounding said shaft and engaged under compression with the upper surface of said third insulating plate.

8. In an electric switch, in combination, a flat insulating base, a plurality of combined contact and wiring terminal members, each of said members comprising a flat sheet metal portion seated upon and secured to the upper surface of said base and an integral terminal portion penetrating said base and exposed below the lower surface of the latter, a flat punched insulating plate superimposed upon said flat sheet metal portions, said plate having certain openings formed therein to provide for exposure of predetermined areas of said flat sheet metal portions and other openings to provide for exposure of corresponding areas of said base, said openings being circularly arranged in equally spaced relationship to each other, means for retaining said base and said plate in substantially fixed relationship to each other, a second flat punched insulating plate positioned above said first mentioned plate and rotatable with respect thereto, a bridging contactor associated with said second plate for rotation thereby, said contactor having diametrically opposed convex portions adapted for movement jointly into and out of alinement with the respective diametrically opposed openings in said first mentioned plate to provide for circuit interruption or for completion of a plurality of different circuit connections in sequence, and means for resiliently biasing said convex portions of said contactor toward said first mentioned plate.

9. In an electric switch, in combination, a flat punched insulating plate, a plurality of combined contact and wiring terminal members, each of said members comprising a flat sheet metal portion seated upon the upper surface of said plate and an integral terminal portion penetrating said plate and exposed below the lower surface of the latter, each of said flat sheet metal portions having a plurality of integral lugs penetrating said plate and bent over the lower surface of the latter to secure said parts in assembled relation, a second flat punched insulating plate superimposed upon said flat sheet metal portions, said second plate having certain openings formed therein to provide for exposure of predetermined areas of said flat sheet metal portions and other openings to provide for exposure of corresponding areas of said first mentioned plate, said openings being circularly arranged in predetermined spaced relationship to each other, means for retaining said plates in substantially fixed relationship to each other, a third flat punched insulating plate positioned above said first mentioned plates and rotatable with respect thereto, a bridging contactor associated with said third plate for rotation thereby, said contactor having diametrically opposed convex portions adapted for movement jointly into and out of alinement with the respective diametrically op-

- posed openings in said second mentioned plate to provide for circuit interruption or for completion of a plurality of different circuit connections in sequence, means for resiliently biasing 5 said convex portions of said contactor toward said second mentioned plate, a shaft of parallel-sided polygonal form in transverse cross section having a positive driving connection with said third plate, and a pair of flat spring members 10 engaged under tension with said shaft at opposite sides of the latter, said spring members acting to insure positioning of said convex contactor portions in alignment with one or another of said pairs of diametrically opposed 15 plate openings upon release of said shaft after a given degree of manual rotation of the latter.
10. In an electric switch, in combination, a metal frame having a top portion and a plurality of equally spaced downwardly extending arms 20 formed integrally with said top portion, said top portion having a centrally located opening formed therein, an externally threaded hollow metal bushing having a reduced lower end penetrating said opening and upset over the lower surface 25 of said top portion to rigidly secure said parts in assembled relation, said top portion having a pair of lugs partially sheared therefrom and bent downwardly at substantially right angles thereto, said lugs being located in a common 30 plane parallel to the plane of one of said arms, said bushing having a pair of parallel flat sides in planes at right angles to the plane of said lugs, a shaft of polygonal form in transverse cross section positioned within said bushing to be 35 centered thereby and extending beyond each end of the latter, said shaft having spaced peripheral grooves formed therein, washers insertable into the respective 40 grooves and engaged with said bushing to prevent substantial endwise displacement of said shaft, an insulating base arranged in a given angular relation to said frame arms and rigidly attached thereto, said base having a diametrically opposed pair of bosses formed upon the upper surface 45 thereof, a flat sheet metal member of arcuate form seated upon the upper surface of said base at one side of and in arcuate alignment with said bosses, said member having a plurality of integral lugs penetrating said base and bent over the 50 lower surface of the latter, said member also having an integral lug penetrating said base to provide for attachment of a circuit wire, a plurality of flat sheet metal members seated upon the upper surface of said base at the other side of and in arcuate alignment with said bosses, said 55 last mentioned members each having a plurality of integral lugs penetrating said base and bent over the lower surface thereof and each also having an integral lug to provide for attachment of a circuit wire, a flat punched insulating plate superimposed upon said base in a given angular relation and engaged by the respective frame arms to restrain said plate against substantial rotary or upward displacement, said plate having a circular series of 60 eight equally spaced openings one diametrically opposed pair of which is aligned with said bosses, other of said openings being adapted to overlie said flat sheet metal members to provide a plurality of diametrically opposed pairs 65 of contact portions, a second punched insulating plate with which said shaft has a positive rotary driving engagement, said second plate having a diametrically opposed pair of openings, a ball contactor in each of said openings, said ball contactors being adapted for movement into alignment with the diametrically opposed pairs of openings in said plate first mentioned, a metal member providing a continuous 70 electrical connection between said contactors, spring means for biasing said contactors toward said first mentioned plate, a metal plate positively rotatable with said shaft, said metal plate having radial shoulders adapted for engagement with said frame lugs respectively to limit the 75

range of rotary movement of said shaft, an insulating operating knob rigidly but removably attached to the upper end of said shaft for positive rotation of the latter, said knob being attached in a predetermined angular relationship to said shaft, and said knob being shaped to cooperate with legends upon a suitable plate to indicate the circuit controlling positions of the switch parts.

12. In a manually operable rotary electric switch, in combination, a stamped sheet metal frame, a flat insulating base carried by said frame, a plurality of stationary contact members superimposed upon said base, a flat insulating plate superimposed upon said base, means independent of said contact members and including a multiplicity of cooperating shoulders on said frame and said plate for restraining the latter against transverse movement relatively to said base, said plate having a plurality of pairs of openings formed therein, certain of said openings overlying the respective contact members to provide for exposure of restricted areas of the latter below the upper surface of said plate, a rotatable bridging contactor having a pair of convex portions movable jointly in either direction into and out of alignment with and into the respective pairs of openings in said plate to provide for completion of a plurality of different circuit connections in sequence, the walls of said openings acting as insulating barriers between the convex portions of said contactor and said contacts upon disengagement of the former from the latter, and a second flat insulating plate associated with said bridging contactor to assist in controlling and guiding such movements of the latter, said second insulating plate being rotatable relatively to said base in closely adjacent relationship to said first mentioned plate to substantially close the upper ends of each opposed pair of openings in said first mentioned plate after disengagement of the convex portions of said contactor from the respective pairs of contact members, for the purpose set forth.

13. In an electric switch, in combination, an insulating base, a plurality of combined contact and terminal members having contact portions superimposed upon said base, certain of said contact portions having a common wiring terminal, a flat punched insulating plate superimposed upon said base, means independent of said contact members for restraining said plate against transverse movement relatively to said base, said plate having a plurality of groups of openings forming opposed pairs, certain openings of one group overlying the contact portions common to said one wiring terminal to thereby provide for exposure of restricted areas of said contact portions below the upper surface of said plate, other of said contact portions being individual to their respective wiring terminals, certain openings of another group overlying the individual contact portions last mentioned to provide for exposure of restricted areas of the latter below the upper surface of said plate, a bridging contactor having a pair of convex end portions movable jointly into and out of alignment with and into the respective pairs of opposed openings in said plate to provide for completion of a plurality of different circuit connections in sequence, the walls of said openings acting as insulating barriers between the convex end portions of said contactor and said contacts upon disengagement of the former from the latter, for the purpose set forth, and an insulating

member associated with said bridging contactor for controlling and guiding such movements of the latter, said insulating member being adapted to overlie and substantially close the upper ends of the respective pairs of opposed openings after disengagement of the convex end portions of said contactor from the stationary contacts associated with said openings. 5

14. In a rotary electric switch, in combination, a punched and stamped sheet metal frame having a substantially flat top part and a plurality of arms formed integrally with said top part and bent downwardly at substantially right angles thereto, said top part having an opening formed therein, a hollow metal bushing having a reduced lower end penetrating said opening and upset over the lower surface of said top part to rigidly secure said elements in assembled relation, said top part having portions thereof partially sheared therefrom and bent downwardly at substantially right angles thereto to provide stop shoulders, a shaft of polygonal form in transverse cross section positioned within said bushing to be centered thereby and extending beyond each end of the latter, said shaft having spaced peripheral grooves formed therein, washers insertable laterally into the respective grooves and engaged with said bushing at the respective ends of the latter to prevent substantial endwise displacement of said shaft, a metal plate having an opening of polygonal contour substantially corresponding to the cross sectional form of said shaft and slidably endwise onto the latter and positively engaged therewith for rotation thereby, means for retaining said metal plate in a given position longitudinally of said shaft, and said metal plate having radial shoulders formed thereon for engagement with the aforementioned stop shoulders respectively to positively limit the degree of rotary movement of said shaft in each direction. 10 20 30 40 50

15. In a rotary electric switch, in combination, a punched and stamped sheet metal frame having a substantially flat top part and a plurality of arms formed integrally with said top part and bent downwardly at substantially right angles thereto, said top part having an opening formed therein, a hollow metal bushing having a reduced lower end penetrating said opening and upset over the lower surface of said top part to rigidly secure said elements in assembled relation, said top part having portions thereof partially sheared therefrom and bent downwardly at substantially right angles thereto to provide stop shoulders, a shaft of polygonal form in transverse cross section positioned within said bushing to be centered thereby and extending beyond each end of the latter, said shaft having spaced peripheral grooves formed therein, washers insertable laterally into the respective grooves and engaged with said bushing at the respective ends of the latter to prevent substantial endwise displacement of said shaft, a metal plate having an opening of polygonal contour slidably endwise onto said shaft and engaged therewith for positive rotation thereby, said metal plate having radial shoulders formed thereon for engagement with the aforementioned stop shoulders respectively to positively limit the degree of rotary movement of said shaft in each direction, a flat punched plate of insulating material to which the lower ends of said frame arms are rigidly attached for support by the latter, a plurality of contact members superimposed upon said plate and rigidly attached thereto, a second flat punched insulating 60 70 80 90 100

plate superimposed upon said insulating plate first mentioned and restrained against substantial movement relatively thereto, said second plate having therein a multiplicity of openings 5 forming opposed pairs, certain of said openings respectively overlying said contact members to provide for exposure of restricted areas of the latter, a bridging contactor having end portions movable jointly into and out of alinement with

the respective pairs of opposed openings in said second plate to provide for completion of a plurality of different circuit connections in sequence, and an insulating member with which said shaft has a positive rotary driving engagement, said insulating member having a positive driving connection with said contactor. 5

ALVIN W. KRIEGER.
